UNITED STATES PATENT OFFICE.

CHARLES A. DAHL, OF LYNN, MASSACHUSETTS, ASSIGNOR TO REECE BUTTONHOLE SEWING MACHINE COMPANY, OF BOSTON, MASSACHUSETTS, A CORPORATION OF MAINE.

EYELET-HOLE-SEWING MACHINE.

SPECIFICATION forming part of Letters Patent No. 699,371, dated May 6, 1902.

Application filed May 31, 1901. Serial No. 62,590. (No model.)

To all whom it may concern:

Be it known that I, CHARLES A. DAHL, a citizen of the United States, residing at Lynn, county of Essex, and State of Massachusetts, have invented an Improvement in Eyelet-Hole-Sewing Machines, of which the following description, in connection with the accompanying drawings, is a specification, like characters on the drawings representing like parts.

10 This application is a continuation of my prior application, Serial No. 690,951, filed September 14, 1898, for an eyelet-hole-sewing machine.

This invention relates to a buttonhole sewing and cutting machine of the type wherein the stitch-forming mechanism has a bodily rotation with respect to the work-clamp and comprises certain improvements in the mechanism for sewing and cutting a buttonhole, 15 which are more fully set forth in the appended claims.

The invention is illustrated in connection with a machine designed more especially for the cutting and sewing of a circular button-hole commonly known as an "eyelet;" but it is obvious that the invention in its main features is equally applicable to buttonholes other than those of circular form.

In the drawings, Figure 1 is a side elevation showing the complete machine. Fig. 2 is a front elevation corresponding to Fig. 1. Fig. 3 is an elevation showing the machine in cross-section upon the line 3 3 in Fig. 1. Fig. 4 is a side elevation showing the machine upon the side opposite to that shown in Fig. 1 and with certain of the parts removed. Fig. 5 is a plan view showing the machine in cross-section on the line 5 5, Fig. 4, with the upper portion of the machine removed. Fig. 6 is a side elevation of a portion of the frame of the machine and the cutting members. Fig. 7 is an enlarged detail view in elevation of various controlling-levers and connections. Fig. 8 is a plan view of the part N, forming a portion of the means for giving the bodily rotation to the stitch-forming mechanism. Fig. 9 is an end elevation of one end of the said part N with its connections. Fig. 10 is a development of the cam-groove 35 in said part N. Fig. 11 is an end ele-

vation of the part N opposite to that shown in Fig. 9. Fig. 12 is an end elevation, partly in cross-section, on the line 12 12 of Fig. 13, showing the part H, which coöperates with the part N. Fig. 13 is a detail view in plan of the 55 said part H. Fig. 14 is a perspective view of the end of the controlling-lever 56 shown in Fig. 7. Fig. 15 is a front elevation showing principally the lower complementary stitch-forming mechanism and the connected parts 60 whereby it is bodily rotated. Fig. 16 is a corresponding rear elevation of the parts shown in Fig. 15. Fig. 17 is a view in cross-section taken upon the line 17 17 of the parts shown in Fig. 16. Fig. 18 is a plan view of the parts 65 shown in Figs. 15, 16, and 17. Fig. 19 is a diagrammatic view showing the paths of the upper and lower needles in connection with the throat-plate. Fig. 20 is a view corresponding to Fig. 19, showing said paths of 70 movement as they appear when viewed at right angles to the position shown in Fig. 19.

The machine illustrated, in common with machines of this type, comprises a clamp-frame A and a stitch-frame B. The stitch-frame has a movement relative to that of the clamp-frame, and in the machine shown the clamp-frame is stationary, while the stitch-frame slides back and forth thereon; but it is obvious that this arrangement may be reversed so long as relative movement of the two frames is provided for.

In the stitch-frame B are mounted or supported the principal operating parts of the machine, including the upper and lower complementary stitch-forming mechanisms, the cutting mechanism comprising a cutter, a cutter-actuating lever, and a cutter-anvil, while on the clamp-frame A is mounted the means for clamping the work to be sewed and cut. 80

Each complete operation of the machine includes a period of time during which the stitch-forming mechanism is at rest and in which the cutting mechanism is operated to cut the buttonhole and a second subsequent 85 period of time in which the cutting mechanism is operated to stitch the buttonhole and a third subsequent period of time in which the machine operates to move the cutting and stitch-forming mechanisms simultaneously in 90 95 100

order to place the said mechanisms in suitable relative relation for beginning the next complete operation of the machine. This entire cycle of operations, it will be understood, 5 is made to take place automatically by a single operation of the manually-controlled starting-lever X X. In carrying out this operation of the machine the pulley 7^x, by which the machine is driven from a suitable source of power, 10 is mounted to turn loosely on the main transverse shaft 6, journaled in the upper portion of the stitch-frame B. This pulley 7^x is connected, by means of a gear 8^x, mounted on the said shaft 6, with a coöperating gear 9^x, mounted 15 upon another parallel transverse shaft 3, mounted in the lower portion of the stitch-frame B, which shaft is normally disconnected from the part H, which it operates at certain times, as hereinafter described. The power 20 is transmitted through the pulley 7^x and operates through the shaft 6 and also through the shaft 3 to operate the various mechanisms of the machine.

The connections whereby the power is transmitted at the required times from the pulley 25 7^x to the shaft 6 are as follows: A disk 80, provided with a segmental flange 81, is rigidly attached to the shaft 6 by a pin 84^x and forms one member of a clutch mechanism for connecting the pulley 7^x with the shaft 6. A second member of the said clutch consists of a disk or annular piece integral or rigidly attached to the pulley 7^x, which disk or annular piece is provided with a projecting rim or 30 flange 85, as shown in cross-section in Fig. 3 and in elevation in Fig. 7. This projecting rim or flange 85 has two oppositely-disposed shoulders formed therein for coöperation with the clutch-pin 82.

40 The clutch-pin 82, whereby the members 81 85 of the clutch are connected at the proper times, is journaled on the hub 80^x of the clutch member 80 and at its lower end resting in a groove 81^y in the flange 81, its other end 45 being shaped, as by being provided with a projection 82^x, to coöperate with the shoulders on the annular projecting rim or flange 85 and also shaped to coöperate with the arm n of the lever 83.

50 The arm n of the lever 83 engages with the end of the clutch-pin 82 and holds the same against the tension of the spring 84 out of position for engagement with the shoulders on the projecting rim or flange 85, carried by 55 the pulley 7^x. When, however, the lever 83 is moved so as to be disengaged from the end of the clutch-pin 82, the spring 84 acts to move the clutch-pin toward and into engagement with the approaching shoulder in the 60 said rim or flange 85 on the pulley 7^x, whereupon the members 81 85 of the clutch are locked together, and the shaft 6 is accordingly revolved in unison with the pulley 7^x until the arm n of the lever 83 engages with the 65 end of the clutch-pin 82 and shifts or disengages it from the shoulder in the rim or flange 85. A buffer-spring 92 is mounted, as shown,

upon the flange 81 and prevents sudden shock in the action of the clutch-pin 82 when the members of the clutch 81 85 are engaged and 70 disengaged.

By means of the shaft 6 motion is imparted through an eccentric 8 on said shaft, a pitman 9 surrounding said eccentric and connecting with a lever 10, pivoted in the upper portion of the stitch-frame B, through connections 11 and 12 to the needle-bar 13, whereby the proper reciprocations of the needle are secured.

The curved under needle 14, which coöperates with the upper needle in making the stitch, is supported in an arm 15, which arm is rigidly attached to one end of the stud 16, journaled obliquely to the horizontal in the block 17. The opposite end of the stud 16 is 85 provided with a gear 18, which coöperates with a similar but larger segmental gear 19, supported for rotative movement on a stud 20 and connected by a link 21 with the rod 22, as shown in Figs. 15, 16, 17, and 18. The gears 90 18 and 19 are suitably beveled to compensate for the inclination of the stud 16 with respect to the stud 20.

The rod 22, which operates the segmental gear 19, is given a reciprocatory movement 95 at the desired times by means of a bell-crank lever 24, pivotally mounted on the stitch-frame to move in a vertical plane. The said lever 24 is connected to the rod 22 by means of a pin 25, slidingly mounted in the end of the lever, which pin 25 is pivotally connected with a sleeve 26, rotatably mounted on the rod 22, as shown in Fig. 1. The lever 24 is rocked by means of the engagement of its opposite end with the grooved cam-disk 23, 105 mounted on the shaft 6.

The above constitutes the mechanism for giving the upper and lower complementary stitch-forming mechanisms the movements for forming the stitch over and through the 110 edge of the buttonhole.

The stitches are placed around the button-hole by giving the entire stitch-forming mechanism a rotation with respect to the work-clamp, and the means for securing this rotation are as follows: A vertical shaft 27 is journaled in the stitch-frame B, as shown, and is provided with laterally-extending arms 28 and 29, one for rotating the upper-needle mechanism and the other for rotating the lower-needle mechanism. These arms 28 and 29 are provided at their outer ends with segmental gears whose center of curvature is the shaft 27, and these segmental gears co-operate, respectively, with the gears 32 and 33, mounted the one on the upper-needle-carrying part 13 and the other on the lower-needle-carrying part or block 17. The shaft 27 has a rearwardly-extending arm x²⁰, consisting, as shown, of an extension of the lower 120 arm 29, and this arm x²⁰ carries an antifriction-roll 34, arranged to travel in the cam-groove 35 in the part N. (Shown in Fig. 8.) This part N is mounted upon a third trans-

verse shaft 37, parallel to the shafts 3 and 6, previously described. Intermittent rotation is imparted to the part N, and thus to the stitch-forming mechanism, to space the 5 stitches around the edge of the buttonhole by the following mechanism: A lever 38 (see Fig. 1) is supported for rocking movement upon the shaft 37, with its upper end in position for engagement with a cam 39, mounted 10 upon the shaft 6, whereby the said lever 38 is rocked forward once during each revolution of the shaft 6. A spring 40 connects the lever 38 with the stitch-frame B and operates whenever cam 39 is out of engagement 15 with the lever 38 to return the lever 38 to its normal position. The lever 38 has a shoulder 41, on which rests the roll 42, and by a spring 43, this roll is normally held in bearing with the face 44 of the flange on the part 20 N. The roll-supporting end face of the shoulder 41 is inclined, so that as the lever 38 is moved forward by the cam 39 it draws the roll 42 into gripping contact with the face 44 of the flange on the part N and gives the 25 part N a fraction of a rotation. This movement is repeated with each succeeding revolution of the shaft 6, the result being a step-by-step movement of the roll 34 in the cam-groove 35, which operates the arm x^{20} , which 30 in turn, through the connection previously described, acts to partially rotate the stitch-forming mechanism, and thereby place the stitches, as required, side by side around the buttonhole. During this step-by-step movement of the part N the roll 34 will travel in the groove 35 from the point 45 to the point 46, (see Fig. 10,) whereupon, as will be understood, the stitch-forming mechanism will have finished its stitching operation and the 35 shaft 6 will be stopped. Another mechanism, hereinafter described, next comes into action through the medium of the clutch 81 82 85, pulley 7^x, and the gears connecting the same to the shaft 3 and a second clutch and the 40 part H and moves the part N to complete its revolution, during which movement the roll 34 will travel in the groove 35 and from the point 46 to the point 45 (see Fig. 10) and during such movement will operate the arm x^{20} 45 and through the same connections as before reverse the rotation of the stitch-forming mechanism, whereby the needles are placed in position for starting the stitching of a succeeding buttonhole.

50 The mechanism above referred to for moving the part N to reverse the rotation of the stitch-forming mechanism and place it in position for starting a buttonhole is as follows: The transverse shaft 3, on which the part H is mounted, carries the rigidly-attached gear 9^x and the rigidly-attached disk 50, which disk is provided with the toothed projections 51 (see Figs. 3 and 5) and forms part of a clutch for connecting at the required times 55 the part H to the shaft 3. On the adjacent end of the part H is a flange 53, and in this flange is stepped one end of a clutch-pin 54,

which pin surrounds the shaft 3 (see Fig. 7) and is pressed normally toward the disk 50 by spring 55 and extends upwardly for engagement at its upper end with the arm e of the bifurcated lever 56. (See Fig. 7.) The lever 56 by its arm e operates to hold the clutch-pin 54 away from the toothed projections 51 on the disk 50, and hence allows the 70 shaft 3 to rotate without rotating the part H; but when the lever 56 is depressed it releases the clutch-pin 54, and the spring 55 then acts to move the upper end of the clutch-pin 54 into engagement with the projections 51 of 75 the disk 50, thus locking the part H fast to the shaft 3.

The part H is shown detached from the other elements of the machine in Fig. 13, and, as shown, carries an eccentric 51^x, (see Fig. 85 1,) which operates the cutter-carrying lever x by means of the connection 6^x, between the said eccentric and the end of the cutter-carrying lever. The part H also carries a cam 4, which is located between depending 90 projections 55 (see Fig. 12) from the clamp-frame A, and hence operates to move the stitch-frame B forward and backward during each complete revolution.

In the operation of the machine the stitch-frame being in its forward position and the cutter about half-way down the operator places the material below the clamping member 4^x of the work-clamp and then shifts the hand starting-lever X X from the position shown by full lines to the position shown by dotted lines in Fig. 7. This lever X X is provided with the two cams 94 96, whereby during the shifting of the said lever the upper clamping member of the work-clamp is depressed to clamp the material below, and the lever 56 is shifted from the position indicated in full lines to the position indicated in dotted lines in Fig. 7. This operation of the lever 56, as before stated, releases the clutch-pin 100 54 from the arm e of the lever 56, and thus 105 clutches the part H to the shaft 3, thus causing the rotation of the part H. The rotation of the part H will continue until the clutch-pin 54 is carried to a position where its free 110 end comes into engagement with the beveled face 57 (see Fig. 14) on the arm a of the lever 56, when, upon the continued rotation of the part H the clutch-pin 54 will ride along the beveled face 57 and be moved toward the 115 part H and out of engagement with the projections 51 of the disk 50, whereupon the part H, having made about three-fourths of a rotation, will be unclutched from the shaft 3 and 120 will stop moving. During this partial rotation of the part H the cutter-carrying lever x by means of the eccentric 51^x will have been operated to cut the buttonhole, and the stitch-frame B will have been moved backwardly by the operation of the cam 4 and the stitching 125 mechanism thus placed in position for beginning the next stitching operation. A cam 58, forming a part of the part H, (see Fig. 7) will 130 also have moved into engagement with and

shifted the lever 83 from the position indicated by full lines to the position indicated by dotted lines in Fig. 7. This movement of the lever 83 will have raised an arm *f* of the said lever sufficiently to disengage the stop 64 on the said arm *f* from the dog 66, and hence to allow the dog 66 to be moved by the spring 65. At the same time the arm *n* of the lever 83 will have swung out of engagement with the clutch-pin 82, allowing the said clutch-pin to be moved by the spring 84 into position for engagement with the next approaching projection in the rim or flange 85 on the loose pulley 7^x to clutch the shaft 6 to said pulley 7^x, whereby the shaft 6 is revolved and the stitch-forming mechanism and the step-by-step feeding mechanism for rotating the stitch-forming mechanism are put into operation, all as hereinbefore described.

20 The lever 83, above referred to, operates in connection with the part N as follows: The dog 66 is mounted to turn loosely on the hub of the part N and is shaped to overlap the shoulder *x*⁸⁰ (see Fig. 8) on the part N and has its periphery coincident with the periphery of the part N. When the parts are in the position shown in dotted lines in Fig. 7, the lever 83 is supported by the stop 64, which rests on both the periphery of the dog 66 and the part N, and 25 it remains thus supported until the step-by-step movement for spacing the stitches has carried the part N into position so that the projection 64 will drop from the shoulder *m* into the recess 67. By this movement the lever 83 is placed with its arm *n* in position to engage the clutch-pin 82, which clutch-pin, riding along the inclined face 90 of said arm *n*, will be drawn out of engagement with the projection in the rim or flange 85 on the pulley 7^x, 30 thus unclutching the shaft 6 from said pulley 7^x and allowing the stitch-forming and feeding mechanisms to cease operation, the stitching of the buttonhole having at this point been completed. The shaft 6 travels at a very 35 high rate of speed, and as the clutch-pin 82 is brought into engagement with the shoulder 60 on the end of the arm 83 the shaft 6 will continue rotating by the momentive force and carry the disk 80 for a limited distance against 40 the force of the springs 92, which movement is sufficient to allow the pawl 61 to spring into the notch 62 on the disk 80, so that after the momentive force is spent and the disk 80 recoils upon operation of the springs 92 it 45 will carry the pawl 61 backward, and thus operate the connections 63, 64, and 65 (shown in Fig. 7) to reverse the hand starting-lever *x* *x*. The hand starting-lever *x* *x* being reversed allows the spring 68 to reverse the lever 56, and therefore shift its arm *a* out from 50 engagement with the clutch-pin 54, whereupon the said clutch-pin is moved by the spring 55 to reengage the disk 50 and clutch the part H to the shaft 3, thus again putting 55 into operation the part H. The rotation of the part H continues during about one-fourth of a rotation of the shaft 3, or an amount governed

by the arc of gear-teeth 70^x, and thereby the clutch-pin 54 is carried into engagement with the inclined face 98 (see Fig. 14) on the arm 70 *e* of the lever 56 and is thereby drawn out from engagement with the projections 51 of the disk 50, and the machine comes to a full stop. During this portion of the rotation of the part H it will have operated the cam 4 75 to move the stitch-frame B forward, and thereby place the cutter-carrying lever *x* in position for the cutter *x*⁸⁰ to cut the material in the work-clamp *x*⁴ with the cutter about half-way down, and during this portion of the 80 rotation the toothed projections 70^x on the part H will have intermeshed with the toothed projections 90^x on the part M, and the part N will have been operated to complete one 85 rotation. During this portion of the rotation of the part N the roll 34 will have traveled in the groove 35 from the point 46 to the point 45 (see Fig. 10) and in so doing will have operated the lever 20^x to reverse the stitch-forming mechanism by rotating the 90 parts 13 and 17, thus leaving the stitch-forming mechanism in position for stitching so far as its rotary position is concerned. It will be noted, however, that the stitch-forming mechanism is in its forward position. The 95 same rotation of the part N, carrying the dog 66, will have placed the dog 66 in engagement with the stop 64 and moved it thereby against the tension of the spring 65 in the position required for repeating its movement 100 when permitted under the stop 54, and the machine may now be put into operation for a second cycle of movement by shifting the hand starting-lever *x* *x*, as previously described.

105 Having described my invention, what I claim as new, and desire to secure by Letters Patent, is—

1. A sewing-machine of the character indicated, comprising a bed-frame, a work-clamping member, an eye-pointed, reciprocating, straight needle located above the clamping member, an eye-pointed, reciprocating curved needle located below the work-clamping member, means to actuate the needles in making the stitches comprising the needle-carrying members as 13 and 17, the part N, having toothed formations and cam-groove 35, and connections substantially as described, with the needle-carrying members 13, 17, and means 110 to partially rotate the part N, step by step, whereby the needles are rotated a full revolution during the stitching operations, combined with a separately-actuated part, as H, having toothed formations adapted for engagement with the toothed formations of the part N, for completing the rotation of part N, whereby the needles are reversely rotated to the starting-point, substantially as described.

115 2. An overedge sewing-machine, comprising a clamp-frame, a work-clamp mounted thereon, a stitch-frame, stitch-forming mechanism mounted thereon, and means for operating it, said stitch-forming mechanism be

ing capable of bodily rotation in said stitch-frame, a cam member, and connections between said cam member and the stitch-forming mechanism whereby upon a single rotation of said cam member the stitch-forming mechanism is bodily rotated in one direction and then bodily rotated in the reverse direction, means for giving a step-by-step movement to said cam member to an extent sufficient to give the desired rotation to the stitch-forming mechanism, and a second means for continuing said movement of said cam member to an extent sufficient to give the desired reverse rotation to the stitch-forming mechanism.

3. A buttonhole-sewing machine comprising stitch-forming mechanism capable of bodily rotation, three shafts, a driven pulley loosely mounted on the first of said shafts and connected with the second of said shafts to rotate the same, a clutch between the pulley and the first shaft, means for intermittently rotating the third shaft from the first shaft, connections between the third shaft and the stitch-forming mechanism whereby the latter may be rotated in either direction, a device loosely mounted on the second shaft and having periodic engagement with the third shaft to operate the same at times, a clutch between said device and the second shaft, connections between the first shaft and the stitch-forming mechanism for operating the same to form stitches, means for actuating the second of said clutches when the machine is set in operation.

4. A buttonhole-sewing machine, comprising stitch-forming mechanism capable of bodily rotation, three shafts, a pulley loosely mounted on the first shaft, a clutch between said pulley and said shaft, connections between the first and second shafts whereby the latter may be driven by the former, a cam mounted on the third shaft and connected with the stitch-forming mechanism to rotate the same, means for giving a continuous rotation to the third shaft from the second shaft at times, means for giving an intermittent rotation to the third shaft from the first shaft at other times whereby intermittent movement may be given to the stitch-forming mechanism in one direction and a continuous movement may be given to the stitch-forming mechanism in the opposite direction.

5. A buttonhole-sewing machine, comprising a rectilineally-reciprocating needle, and means for operating it, lower complemental stitch-forming mechanism comprising a curved needle pivoted at an oblique angle to the path of reciprocation of the needle upon

a rotary support, the said rotary support, 60 means for rotating said support, and means for operating the curved needle.

6. A buttonhole-sewing machine, comprising a rectilineally-reciprocating needle, and means for operating it, lower complemental 65 stitch-forming mechanism, comprising a curved needle pivoted at an oblique angle to the path of reciprocation of the needle upon a rotary support, the said rotary support, means for rotating said support, and means 70 for giving a variable movement to the said curved needle.

7. A buttonhole-sewing machine comprising a rectilineally-reciprocating needle, and means for operating it, lower complemental 75 stitch-forming mechanism comprising a thread-carrier mounted upon a shaft, said shaft being arranged at an oblique angle to a path of reciprocation of the needle, a gear upon the end of said shaft, a second gear co-operating therewith and mounted for rotary movement in a plane parallel with the path of reciprocation of the needle, a rod or bar connected to the second gear and reciprocating in a path parallel to the path of the needle, 80 and means for reciprocating said rod or bar, a rotary support for said complemental stitch-forming mechanism and means for rotating said support.

8. A buttonhole-sewing machine comprising 90 stitch-forming mechanism capable of bodily rotation, three shafts, buttonhole-cutting mechanism, means for moving the stitch-forming mechanism relatively to the cutting mechanism, connections between the first 95 shaft and the second shaft for operating the latter connections between the first shaft and the stitch-forming mechanism for operating the same to form stitches, connections between the second shaft and the cutting mechanism for operating the same, connections between the third shaft and the stitch-forming mechanism for rotating the same in either direction, means for operating the third shaft intermittently from the first shaft to rotate 100 the stitch-forming mechanism step by step during the stitching of the buttonhole, means to operate the third shaft continuously from the second shaft to rotate the stitch-forming mechanism continuously in the direction opposite to that obtained during the stitching.

In testimony whereof I have signed my name to this specification in the presence of two subscribing witnesses.

CHARLES A. DAHL.
